UNITED STATES PATENT OFFICE.

GEORGE BENJ. STEINHAUER, OF READING, PENNSYLVANIA.

ARM-REST.

SPECIFICATION forming part of Letters Patent No. 443,839, dated December 30, 1890.

Application filed July 29, 1890. Serial No. 360,290. (No model.)

To all whom it may concern:

Be it known that I, GEORGE BENJ. STEINHAUER, a citizen of the United States, and a resident of Reading, in the county of Berks 5 and State of Pennsylvania, have invented certain new and useful Improvements in Arm-Rests; and I do hereby declare that the following is a full, clear, and exact description of the invention, which will enable others skilled in the art to which it appertains to make and use the same, reference being had to the accompanying drawings, which form a part of this specification.

My invention relates to improvements in 15 arm-rests adapted to be placed upon a store-counter, table, or other object for the purpose of supporting the arm while a glove is being fitted to the hand.

As now ordinarily practiced, much difficulty 20 is experienced in fitting kid gloves to the hand, owing to the fact that there is no support for the arm, thus rendering the operation not only very tiresome to the person to whose hand the glove is being fitted, but also very troublesome to the operator.

The object of my invention is to provide a 25 simple, economical, and efficient device by which the arm can be supported while a glove is being fitted to the hand, whereby the operation is facilitated and the labor decreased.

The invention consists in the novel construction and combination of parts herein-after described, and specifically defined in the claims.

In the accompanying drawings, Figure 1 is 30 a side view of an arm-rest constructed in accordance with my invention. Fig. 2 is a central vertical section of the same. Fig. 3 is a plan view.

In the said drawings, the reference-numeral 40 1 designates a rectangular plate, of wood, metal, or other suitable material, which forms the base or support for the arm-rest 2. This rest is preferably made of metal, and consists 45 of a base portion 3, formed with or secured to the plate 1. The base portion is centrally recessed, forming a seat for the elbow, and may be provided with a pad 4, which forms a cushion for the elbow.

Extending upwardly from opposite sides of

the base 3 are the curved supports 6 and 5 to receive, respectively, the forearm and that portion of the arm between the elbow and shoulder. It will be noticed that the portion 6 is somewhat longer than the part 5, so that 55 when the arm is placed in the rest the hand and wrist will project outwardly therefrom. These parts 5 and 6 are made to conform to the shape of the arm, so that the same will fit snugly therein.

In the plate 1, immediately in front of the arm-rest, is an annular flange 7, forming a receptacle for a powder-can 8. This can is designed to contain powder to be placed upon the hands for facilitating the operation of putting on the gloves, and may be secured in place by means of the spring 9.

The operation will be readily understood. The person to whose hand the glove is to be fitted places the arm in the rest, the elbow being supported upon the pad in the base 3, the forearm resting in support 6 and the upper portion of the arm in the support 5. The hand and wrist will project beyond the support 6, thus enabling the operator to fit the glove with 75 but little trouble, as the arm is rigidly supported and prevented from movement, and the operation will be less tiresome to the arm.

Instead of securing the rest to the base 1, it may be secured directly to a counter or 80 other object, although I prefer to form it with said base, so that it can be moved from place to place, as described.

Having thus described my invention, what I 85 claim is—

1. An arm-rest adapted to be secured to a counter or other object, consisting of a base forming an elbow-seat and opposite upwardly-extending supports for the fore and upper parts of the arm, substantially as described. 90

2. An arm-rest consisting of a base forming an elbow-seat and opposite upwardly-extending curved supports for the fore and upper parts of the arm, and a base-plate to which said rest is secured, substantially as described. 95

3. An arm-rest consisting of a recessed base with a pad or cushion located therein, forming an elbow-seat, opposite upwardly and outwardly extending curved supports for the fore and upper parts of the arm, and a base-plate 100

to which the rest is secured, substantially as described.

4. The combination, with an arm-rest consisting of a recessed base having a pad or cushion thereon and upwardly and outwardly extending curved supports, of a base-plate having an annular flange forming a seat for a powder-can, and a retaining-spring, substantially as described.

In testimony that I claim the foregoing as to my own I have hereunto affixed my signature in presence of two witnesses.

GEORGE BENJ. STEINHAUER.
